UNITED STATES PATENT OFFICE.

JAMES J. SMITH, OF LATROBE, PENNSYLVANIA.

SWITCH.

SPECIFICATION forming part of Letters Patent No. 712,973, dated November 4, 1902.

Application filed April 1, 1902. Serial No. 100,980. (No model.)

To all whom it may concern:

Be it known that I, JAMES J. SMITH, a citizen of the United States of America, residing at Latrobe, in the county of Westmoreland and State of Pennsylvania, have invented certain new and useful Improvements in Switches, of which the following is a specification, reference being had therein to the accompanying drawings.

- 10 This invention relates to certain new and useful improvements in switches, and has for its object the provision of novel means whereby the frog may be easily turned to open or close the switch.
- 15 The invention has for its further object to provide a device of the above-described character that will be extremely simple in construction, strong, durable, comparatively inexpensive to manufacture, and highly efficient in its use.

20 With the above and other objects in view the invention consists in the novel construction, combination, and arrangement of parts, to be hereinafter more fully described, and 25 specifically pointed out in the claim.

30 In describing the invention in detail reference is had to the accompanying drawings, forming a part of this specification, and wherein like numerals of reference indicate like parts throughout the several views, in which—

35 Figure 1 is a top plan view of my improved frog. Fig. 2 is a vertical sectional view thereof, taken on the line 2 2 of Fig. 1. Fig. 3 is an enlarged perspective view of the crank-arm and eccentric to operate the switch-frog. Fig. 4 is an underneath detail view of the switch-frog.

40 In the drawings, the reference-numeral 1 represents the base-plate, and 2 represents the rails. The switch-frog 3 is pivotally secured at 4 upon the base-plate. The said frog has formed in its under face a recess 5 and carries at its rear end a lug 6, said lug operating in the recess 7, formed in the raised portion of 45 base-plate, which is arranged between the for-

ward ends of the rails 2. A cam or eccentric 8 is secured in the recess 5 and has attached thereto a shaft 9, to which is secured a crank-arm 10. This crank-arm 10 is connected to an operating-rod 11, which leads to the switch- 50 stand and may be operated by any suitable mechanism.

It will be seen that by operating the rod 11 movement will be imparted to the crank-arm 10, which will operate the cam, and the latter in turn will move the frog in one direction or the other, either to open or close the switch. It will further be noted that the lug 6 operating in the recess formed in the base- 55 plate will perfectly guide the frog in its move- 60 ment.

The many advantages obtained by the use of my improved device will be readily apparent from the foregoing description, taken in connection with the accompanying drawings. 65

It will be noted that various changes may be made in the details of construction without departing from the general spirit of my invention.

Having fully described my invention, what 70 I claim as new, and desire to secure by Letters Patent, is—

75 The combination of the switch-frog having its under face recessed and provided at its rear end with a lug, of a plate provided with a raised portion having a recess therein, said frog pivotally mounted on said plate and having its lug in the recess of the said raised portion, a shaft journaled in the said plate, a cam secured to the upper end of the said shaft and arranged in the recess of the said frog, a 80 crank-arm and means for operating the said crank-arm, substantially as described.

In testimony whereof I affix my signature in the presence of two witnesses.

JAMES J. SMITH.
